UNITED STATES PATENT OFFICE.

CARL O. JOHNSON, OF NEW YORK, N. Y.

DESIGN FOR A DISPENSING CABINET.

Application filed June 12, 1926. Serial No. 18,018. Term of patent 3½ years.

To all whom it may concern:

Be it known that I, CARL O. JOHNSON, a citizen of the United States, residing in New York city, borough of Manhattan, in the county and State of New York, have invented a certain new, original, and ornamental Design for Dispensing Cabinets, of which the following is a specification, reference being had to the accompanying drawings, of which—

I claim:

The ornamental design for a dispensing cabinet as shown.

CARL O. JOHNSON.
